(57) **CLAIM**

I claim the ornamental design for a three section foldable clipboard with a holder for a writing implement, as shown and described.

DESCRIPTION

FIG. 1 is a perspective view of a three section foldable clipboard with a holder for a writing implement in an unfolded, expanded position and having a first section, a second section, and a third section;

FIG. 2 is a perspective view of the three section foldable clipboard with a holder for a writing implement with the first section and the third section partially folded toward the second section;

FIG. 3 is a perspective view of the three section foldable clipboard with a holder for a writing implement in a folded position with the third section folded over the second section and the first section folded over the third section;

FIG. 4 is a top plan view of the three section foldable clipboard with a holder for a writing implement in the unfolded position;

FIG. 5 is a bottom plan view of the three section foldable clipboard with a holder for a writing implement in the unfolded, expanded position;

FIG. 6 is a right side view of the three section foldable clipboard with a holder for a writing implement in the unfolded, expanded position;

FIG. 7 is a left side view of the three section foldable clipboard with a holder for a writing implement in the unfolded, expanded position;

(Continued)

FIG. 8 is a top plan view of a lower end of the three section foldable clipboard with a holder for a writing implement in the unfolded, expanded position; and,

FIG. 9 is a top plan view of an upper end of the three section foldable clipboard with a holder for a writing implement in the unfolded, expanded position.
